DESIGN FOR AN ARTIFICIAL FLOWER BOUTONNIERE

Florence N. Lewis, New York, N. Y., assignor to Elizabeth Arden, Inc., New York, N. Y., a corporation of New York

Application June 11, 1938, Serial No. 77,746

Term of patent 3½ years

To all whom it may concern:

Be it known that I, Florence N. Lewis, a citizen of the United States, residing at New York, in the county of New York and State of New York, have invented a new, original, and ornamental Design for an Artificial Flower Boutonniere, of which the following is a specification, reference being had to the accompanying drawing, forming part thereof.

The drawing illustrates a front elevational view slightly in perspective of an artificial flower boutonniere showing my new design.

My design consists of four artificial flowers, each having a perfume container embedded therein and arranged on a plume background as shown.

I claim:

The ornamental design for an artificial flower boutonniere, as shown and described.

FLORENCE N. LEWIS.
